[57] CLAIM

The ornamental design for a combined organizer for desk accessories and rotary file, as shown and described.

DESCRIPTION

FIG. 1 is a top, right front perspective view of a combined organizer for desk accessories and rotary file showing my new design;

FIG. 2 is a front elevational view;

FIG. 3 is a side elevational view, the opposite side being a mirror image thereof;

FIG. 4 is a top plan view;

FIG. 5 is a bottom plan view; and,

FIG. 6 is a top, right front perspective view in an exploded condition.

FIGS. 2 through 5 have been drawn to a reduced scale with respect to FIGS. 1 and 6.

FIG. 1

FIG. 2

FIG. 3

FIG.4

FIG.5

FIG. 6
